UNITED STATES PATENT OFFICE.

CLAUDE N. ALLEN, OF MICHIGAN CITY, INDIANA.

CARPET-CLEANER.

1,164,904.

Specification of Letters Patent. Patented Dec. 21, 1915.

Application filed February 10, 1915. Serial No. 7,396.

To all whom it may concern:

Be it known that I, CLAUDE N. ALLEN, a citizen of the United States, residing at Michigan City, in the county of LaPorte and State of Indiana, have invented new and useful Improvements in Carpet-Cleaners, of which the following is a specification.

This invention relates to carpet-cleaners and the object of the invention is to provide a simple and efficient beater which may be transported from place to place conveniently and operated to rapidly and thoroughly clean the carpet of all the dust and dirt.

Another object of the invention is the provision of a device of this character wherein the beater may be operated upon a carpet lying upon the ground or other flat surface while the operator occupies a standing position, thus avoiding any stooping and rendering the work less arduous.

Further objects of the invention will appear as the following description is read in connection with the accompanying drawing, which forms a part of this application, and in which:

Figure 1 is a top plan view. Fig. 2 is a vertical section taken on the line 2-2 of Fig. 1. Fig. 3 is a side elevation. Fig. 4 is a detail sectional view taken on the line 4-4 of Fig. 3.

Referring more particularly to the drawing, 1 represents the base constructed of any suitable material and which may be supported above the floor or ground in any suitable manner, which will facilitate the transportation of the device and its movement over the carpet. Secured to and projecting above the base are separated side plates 3 connected together at one end by a cross bar 4 in which plates is journaled the driven shaft 5 projecting through one of the side plates where it has secured thereto a disk 6. This disk carries a pair of separated clamping devices 7 between which the handle end of an ordinary carpet beater 8 is secured.

Keyed to the shaft 5 is a pinion 9 in mesh with the gear 10 arranged upon the driving shaft 11 journaled in a frame 12 which is mounted upon shaft brackets 13 carried by the shaft 5. This frame is constructed of separated side members joined together at one end by the sleeve bolt 14 and supported at its opposite end by a hanger 15 depending from the cross bar 4. The gear 10 has secured to it an operating handle 16, as shown, which when oscillated from side to side will rotate the shaft 5 and forcibly move the beater in a direction opposite to the movement of the handle. The handle is preferably constructed of adjustably connected sections so that the operator may manipulate the same when either in a sitting position or standing. By forcibly moving the handle back and forth, as will be readily understood, the free end of the beater will slap the carpet or other article to be cleaned, thereby knocking the dust or dirt from the same.

What is claimed is:

1. In a carpet cleaner, a base, supports carried thereby, a shaft journaled in the supports, means for attaching a beater at right angles to the end of the shaft, a frame mounted upon the shaft and connected to said supports, a shaft journaled in the frame, an intergeared connection between said shafts, and means for oscillating said second shaft.

2. In a carpet cleaner, a portable base, a horizontally positioned oscillatable shaft mounted upon the base, means for connecting the beater at right angles to the shaft, means carried by the oscillatable shaft for oscillating the same and means for preventing rotation of said means with the shaft.

In testimony whereof I affix my signature in presence of two witnesses.

CLAUDE N. ALLEN.
